UNITED STATES PATENT OFFICE.

JACKSON O. HAAS, OF PHILADELPHIA, PENNSYLVANIA.

HAT.

1,093,777.

Specification of Letters Patent. Patented Apr. 21, 1914.

Application filed September 11, 1913. Serial No. 789,230.

To all whom it may concern:

Be it known that I, JACKSON O. HAAS, a citizen of the United States, residing at Philadelphia, in the county of Philadelphia and State of Pennsylvania, have invented 5 certain new and useful Improvements in Hats, of which the following is a specification.

My invention relates to improvements in 10 hats, the object of the invention being to provide a hat which may be readily packed in a suit case or trunk and which will not occupy the space of an ordinary hat.

A further object is to provide a hat, as for 15 example, a straw hat in which the crown and rim may be separated and securely held together when desired.

A further object is to provide an improved 20 hat which permits the portions thereof to be reversed whenever desired.

With these and other objects in view, the invention consists in certain novel features of construction and combinations and arrangements of parts as will be more fully 25 hereinafter described and pointed out in the claims.

In the accompanying drawings: Figure 1 is a view in longitudinal section partly 30 broken away illustrating one form of my improvements. Fig. 2 is a similar view illustrating a modification. Fig. 3 is a view in section on the line 3—3 of Fig. 2. Fig. 4 is a perspective view of one of the elastic straps illustrated in Fig. 2, and Figs. 5, 6, 7, 35 8, 9, 10, 11, and 12, are views illustrating other modifications.

Referring to Fig. 1, 1 represents the crown 40 of the hat and 2 the rim. These parts are entirely independent of each other and may be straw or other material.

The lower edge of the crown 1 is flared 45 outward slightly forming a projecting flange 3 against the under face of which the rim 2 is held by an elastic cord 4. This cord 4 is secured to the rim 2 as shown at 5, and between such securing points is caught over hooks 6 secured to the inside of the crown of the hat to elastically hold the crown and rim together. A sweat band 7 is secured to the 50 rim and covers the lower portion of the elastic cord.

In Fig. 2, the crown 1 and rim 2 are constructed as in Fig. 1 with the exception that the rim 2 has an opening large enough to 55 receive the crown, and rests upon the upper edge of the flange 3, and not against the

lower edge thereof as in Fig. 1. In this form of my invention, I have illustrated as a connecting means, a plurality of elastic straps 8 in lieu of the elastic cord 4. These straps 8 are secured to the rim 2 and passed around the lower edge of crown 1. Rings 9 are provided at the free ends of the straps to engage over the hooks 6 and hold the parts together. 60

By providing an elastic connecting means between the crown and the rim, the latter exerts a continuous pressure or pull on the parts so that they are held tightly together which is desirable in excluding rain and 65 moisture which might form on the rim or crown of the hat. Furthermore, the elastic connection enables the connecting medium to be more conveniently handled than would be the case if it were not elastic as the connecting devices will stretch and allow the parts to be connected and disconnected. 70

In the modification illustrated in Fig. 5, a plurality of spring metal catches 10 are secured to the rim 2, and are sprung over an 80 internal ring 11 fixed within the crown 1. These spring catches 10 are preferably part of a metal ring 12 covered by the sweat band 7.

In the modification illustrated in Fig. 6, 85 headed studs 14^a are secured in the crown 1, and are engaged by recessed spring tongues 15 on a metal ring 16 corresponding to the ring 12 of Fig. 5.

In the modification illustrated in Figs. 90 7 and 8, the crown of the hat comprises a top piece 13 and a strip 14 which is provided adjacent its ends with openings 15 for the reception of a lacing cord 16 to secure the band in shape to conform to the 95 shape of the crown. The top piece 13 has a plurality of openings 17 through which hooks 18 are projected, and these hooks 18 are engaged by an elastic cord 19. The cord 19 is positioned through tongues 20 secured to the rim 2, so that by means of this 100 elastic cord, the hat is held together.

In the modification illustrated in Figs. 9 and 10, the top 13 is provided with pairs of openings 20^a so that the elastic cord 19 105 may be laced through them and operate to hold the rim and crown together. In this form of my invention, I have shown an integral tab 21 on one end of the strip 14 which is separably connected by a snap button 22 with the other end of the strip to secure the strip in proper formation. 110

In Fig. 11, I illustrate a modification in which the top 13 is provided on its inner face with hooks 23 to be engaged by rings 24 on elastic straps 25 secured to the rim 2.

5 In Fig. 12, I illustrate a modification in which the top 26 is connected to the rim 27 by means of a plurality of toggle levers 28, the side portions 29 of the crown being flexible so that the crown may be readily col-
10 lapsed as shown in Fig. 12.

With all of the different forms of my invention, the object is to so construct the hat that it may be readily adapted or will occupy but small space, and a further object
15 with several of the forms of my invention is to permit the parts to be reversed so that when they become dirty on the top or on the outside, they can be reversed and present a clean appearance.

20 Various slight changes might be made in the general form and arrangement of parts described without departing from my invention, and hence I do not limit myself to the precise details set forth, but consider
25 myself at liberty to make such changes and alterations as fairly fall within the spirit and scope of the appended claims.

Having thus described my invention, what I claim as new and desire to secure by
30 Letters Patent is:

1. As a new article of manufacture, a hat comprising a crown having an outwardly flared lower edge, a rim adapted to be positioned against the outwardly flared lower
35 edge, means within the crown securing the rim against said outwardly flared lower edge, said means comprising an elastic cord laced upwardly and downwardly from the rim to the upper portion of the crown and
40 connected to both the rim and the crown, substantially as described.

2. As a new article of manufacture, a hat comprising a crown having an outwardly flared lower edge, a rim adapted to be positioned against the outwardly flared lower edge, and elastic means connecting the rim with the inner portion of the crown, said means comprising an elastic cord laced upwardly and downwardly from the rim to
45 the upper portion of the crown and connected to both the rim and the crown, substantially as described.

50 3. As a new article of manufacture, a hat

comprising a crown and a rim, said crown composed of a top piece and a band, means 55 at the ends of the band securing the band in shape conforming in shape to the top piece, and coupling means connecting the top piece, the band, and the rim, said means comprising an elastic cord laced upwardly 60 and downwardly from the rim to the upper portion of the crown and connected to both the rim and the crown, substantially as de-
scribed.

4. As a new article of manufacture, a hat 65 comprising a crown, a rim independent of the crown, and elastic means securing the crown and rim together, substantially as described.

5. As a new article of manufacture, a hat 70 comprising a crown having an outwardly flared lower edge, a rim adapted to be positioned against the outwardly flared lower edge, and means within the crown securing the rim against said outwardly flared lower 75 edge, substantially as described.

6. As a new article of manufacture, a hat comprising a crown having an outwardly flared lower edge, a rim adapted to be positioned against the outwardly flared lower 80 edge, and elastic means connecting the rim with the inner portion of the crown, sub-
stantially as described.

7. As a new article of manufacture, a hat comprising a crown having an outwardly 85 flared lower edge, a rim adapted to be positioned against the outwardly flared lower edge, hooks within the crown, and elastic means connecting the rim with said hooks, substantially as described. 90

8. As a new article of manufacture, a hat comprising a crown and a rim, said crown composed of a top piece and a band, means 95 at the ends of the band securing the band in shape conforming in shape to the top piece, and coupling means connecting the top piece, the band, and the rim, substan-
tially as described.

In testimony whereof I have signed my name to this specification in the presence of 100 two subscribing witnesses.

JACKSON O. HAAS.
